CLAIM

We claim the ornamental design for a wrist strap, as shown and described.

DESCRIPTION

FIG. 1 is a rear perspective view of a wrist strap in accordance with the present invention;

FIG. 2 is a front perspective thereof;

FIG. 3 is a top view thereof;

FIG. 4 is a bottom view thereof;

FIG. 5 is a left view thereof;

FIG. 6 is a right view thereof;

FIG. 7 is a front view thereof; and,

FIG. 8 is a rear view thereof.

The broken lines shown in the drawings illustrate portions of the wrist strap that form no part of the claimed design.
